(57) **CLAIM**

The ornamental design for hole saw, as shown and described.

DESCRIPTION

FIG. 1 is a perspective view of a first embodiment of a hole saw showing the present invention;
FIG. 2 is a front elevational view thereof;
FIG. 3 is a rear elevational view thereof;
FIG. 4 is a left side elevational view thereof;
FIG. 5 is a right side elevational view being thereof;
FIG. 6 top plan view thereof; and,
FIG. 7 is a bottom plan view thereof.
The broken lines in the figures show structure or boundaries that are not part of the claimed design.

1 Claim, 2 Drawing Sheets
